READING MACHINE

Robert Place, Waltham, Mass., assignor to
 Graphic Service Corporation, Boston, Mass., a
 corporation of Massachusetts

Application September 21, 1939, Serial No. 295,962

16 Claims. (Cl. 88—24)

This invention relates to improvements in projection apparatus of the kind known as reading machines and embraces cabinets therefor.

A general object of the invention is to provide a reading machine which is of compact construction, simple in operation and durable in use, all in contrast with the relatively complex devices heretofore provided.

It is also an object to provide a reading machine, so arranged and supported relative to the projection cabinet, that, in one position, it will permit viewing a complete newspaper page or other matter disposed vertical to the edge of the film and, in another position, will permit reading of copy running parallel to the edge of the film, such as smaller books.

Another object is to provide a reading machine in which all or various selected parts may be positively driven without the necessity of using friction clutches, belts or other friction means which are subject to excessive wear and maladjustment.

Another object is to provide a reading machine control system whereby the film advance, rewind, focus and scanning position, all or in any combination, may be operated from a single control center and with one hand. In one form of the invention, coaxial control shafts may be provided, rotatably and axially movable relative to each other when operating various parts of the machine.

A further object is to provide an improved film gate or glass flat opening and closing mechanism whereby the actuation is positive and the film may remain in the same focus both while advancing and while the flats are closed in the normal reading position.

A still further object is to provide an improved mechanism for adjusting the film vertically to its normal advance and rewind position for scanning purposes, as for example, to bring any column of a newspaper to the center of the screen, which mechanism may be conveniently controlled from the same center as the film advance and focus.

My invention also embraces a novel projection cabinet and arrangement of the projection mechanism relative to the cabinet and, among the objects and advantages relative to these features, is to provide a cabinet having a shadow box around the screen surface to shield extraneous light and afford the reader complete privacy; a cabinet having a desk shelf to provide writing space for taking notes and the like, thus eliminating any need for separate tables or other fur-

niture; a viewing screen slidably mounted relative to the cabinet to provide for magnification if desired; a cabinet including an enlargement slide which may be used for making prints of the projected subject matter; and an arrangement of the projection apparatus relative to the cabinet whereby it may be enclosed within the cabinet normally and when in operation and readily opened into loading position at the lap of the seated operator.

Other objects and advantages of the invention will be apparent from the following detailed description taken in conjunction with the accompanying drawings wherein preferred embodiments of the principles of the invention have been selected for exemplification.

In the drawings:

Fig. 1 is a side elevational view of a reading cabinet showing a projector hingedly supported therein;

Fig. 2 is a front elevation of the cabinet of Fig. 1;

Fig. 3 is a side elevation of a modified portable cabinet having a projector supported in a drawer;

Fig. 4 is an enlarged plan view of a projector embodying the principles of the present invention and positioned vertically;

Fig. 5 is a side elevation of the projector of Fig. 4 from the film side;

Fig. 6 is a face view of the projector of Fig. 4 taken from the side opposite from that shown in Fig. 5 with the casing removed;

Fig. 7 is a plan view of the device of Fig. 6 with the casing in section;

Fig. 8 is a sectional view on line 8—8 of Fig. 6 looking in the direction of the arrows and showing the film gate cam operating means;

Fig. 9 is a transverse section on line 9—9 of Fig. 6 looking in the direction of the arrows; and

Fig. 10 is an enlarged detail prospective of the film gate actuating member.

Referring more particularly to the drawings wherein like numerals refer to like parts, the letter A in Figs. 1 and 2 designates in its entirety a reading cabinet having the image projecting mechanism 10 mounted upon a hinged panel 12 of the cabinet, in operative position when the panel is closed, as shown, and in convenient position for lap re-loading when the panel is swung open. A mirror 14 is adjustably mounted in the cabinet A opposite the projector 10 and a viewing screen 16 receiving the reflected image from the mirror 14 is recessed from the front of the cabinet above the projector in con-

venient line of vision of the operator seated before the projector control handle 11 protruding from the lower front portion of the cabinet. The screen 16 may be mounted in a sleeve 15 to shield extraneous light and afford privacy to the reader and which slides in and out of the cabinet permitting magnification of the image on the screen. Recessing of the screen 16 relative to the cabinet also provides a convenient space for mounting a desk shelf 17 for use of the reader in taking notes and the like thus avoiding any need for separate desks or tables and making the cabinet a complete reading and desk unit.

The cabinet A may receive a projector unit according to the present invention and designed to project horizontally on the viewing screen 16 images photographed either vertically or horizontally on the film and mounted in the cabinet to swing on its horizontal axis in a 90° arc. An arcuate slot such as at 13 in Fig. 2 may be provided in the cabinet projector supporting wall to receive the shaft forming a part of the protruding control members 11 which pivot with the projector as a unit.

A modified form of cabinet designed as a portable unit to be operated on a table or the like is represented in its entirety by B in Fig. 3. The projector 10 for the cabinet B may be horizontally mounted in a sliding drawer, slideable with the drawer for focusing and in convenient position for lap re-loading when the drawer is open, as shown. A mirror 20 is adjustably mounted in the cabinet B opposite the projector 10 and a smooth surfaced screen 22 receiving the reflected image from the mirror 20 is mounted at the front of the cabinet above the drawer 18 to support tracing paper for tracing the image. Hinged viewing screen 2 may rest atop the cabinet or overlay screen 22 as desired.

The rear of cabinet B may be provided with an adjustable leg 19 to maintain the device in a selected position convenient to the operator and at its front portion may have a partitioned compartment 21 for storing films or the like and accessible through a hinged door forming a part of the front wall above the drawer 18.

An important feature of the invention shown embodied in the cabinet B of Fig. 3 involves the provision of means including an enlargement slide 23 for the purpose of making prints of the projected subject matter and, in conjunction therewith, mirrors 25 and 27 are hingedly supported in the lower and upper portions of the cabinet, respectively, and swingable to position in the normal light path to deflect the same from the screen 22 and project the image into the area of enlargement slide 23.

A preferred manner of mounting the projector 10 is apparent in Figs. 4 and 5. Adjustably secured to the hinged panel 12 or drawer or other wall portion of the cabinet is a lighting system comprising a base 24 fixed to the wall in any predetermined position, an integral lamp housing 26 having heat radiating fins 29 and a sleeve 32. The head 30 of the projecting unit may be provided with a condenser system including a tube 28 tending to rotate within the sleeve 32 and limited in its relative movement to a 90° arc by a stud 34 projecting from the condenser and riding in a slot 36 of appropriate length cut in the sleeve wall. A pin 31 carried by a bellcrank lever or the like 33 and operable by a button 35 in the front wall of the casing may extend through the lamp housing 26 to selectively engage one of a pair of sockets 37 provided in adjacent extremities of

the condenser tube 28 and the sleeve 32 to lock the head 30 in either of its extreme pivoted positions. A spring pressed plunger 131 may be received in the base member 24 to bear against the pin 31 urging the same into a socket 37. The head 30 is thus supported in the cabinet guided as to its pivotal movement for horizontal or vertical projection while the lighting system remains stationary serving as the pivotal axis for the head 30.

As best shown in Fig. 6, the lamp housing 26 may have the lamp socket 39 anchored to a disc 41, the disc in turn being secured to a portion of the base member 24 by a single screw or the like 43 which allows the lamp and its socket to be twisted to correct the filament direction.

The head 30 may be boxed by top and bottom walls 38 and 40 and continuous side and end walls 42 and 44, respectively. Supported exteriorly of the top wall 38 of the head 30 are film reels 46 and 48 mounted on spindles 50 and 52, respectively. The film 54 loaded on the reels 46 and 48 is passed around film guides 56 bolted or otherwise secured to the wall 38 and projecting exteriorly thereof astride the free end portion of the condenser tube 28.

Immediately forward of the condenser tube, the wall 38 is provided with a pair of parallel slots 62 and, bordering the length thereof, a pair of angle irons 64 each having a pair of apertures 66 and 67 for, respectively, receiving pins 68 and 69 integral with opposed pairs of arms 70 and 72 to thereby pivotally support the arms 70 and 72 with respect to the wall 38. Springs 73 may be carried by the depending portion of angle members 64 to bear against arms 70 and 72 urging them together. Carried by the upper extremities of opposed pairs of arms 70 and 72 are frames 74 and 76, respectively, supporting glass plates or flats 78 and 80, each held in its frame by means of springs 82 and forming a film gate. Thus, each plate 78 and 80 is mounted so as to be movable relative to the other and away from the normal film line allowing the film to remain in the same focus both while advancing when the flats 78 and 80 are open and while in normal reading position when the plates are closed.

A suitable projecting lens system is mounted in alignment with the film gate and condenser 59 and includes a boss 84 integral with or mounted upon the forward end of wall 38 and slidably receiving a lens barrel 86 carrying a rack 88 operable for focusing the projected image as herein-after described.

Coming now to the operating and control means, a hollow control shaft 90 having a solid concentric shaft 92 extends from outside the cabinet through the slot 13 in the wall thereof and through the end wall 44 into the head 30 forming a line of drive which may be substantially parallel to the ground or other cabinet support and at an acute angle to the line of projection formed along the axis of the pivoted head 30 which is directed slightly upwardly toward the image or light reflecting mirror 14. Of course, it is within the scope of the invention to arrange the lines of drive and projection in parallel or at any other convenient angle as may be desired, but the foregoing arrangement has been found particularly suitable in the larger reading machines capable of projecting and viewing a variety of different subject matter, including a complete newspaper page.

Keyed to an intermediate portion of the shaft 75 90 interiorly of the head 30 is a beveled drive

gear 94 meshing with a complementary driven gear 96 fastened to a sleeve 98 upon which a carrier plate 100 is mounted. A driving gear 99 of relatively large diameter is fastened on the upper portion of the sleeve 98 and is permanently in mesh with transfer pinions 102 and 104 mounted on pins 106 and 108 secured to the carrier plate. Pinions 110 and 112 are fastened to film reel spindles 50 and 52, respectively, and lie in the same plane as transfer pinions 102 and 104 to selectively mesh therewith. When the shaft 90 is rotated in a counter-clockwise direction, the carrier 100 will be swung in a clockwise direction, bringing transfer pinion 104 into mesh with pinion 112 to rotate spindle 52 and its reel 48 in a clockwise direction away from companion reel 46 which is free to rotate since the pinion 110 fastened to its spindle 50 is then out of mesh with transfer pinion 102. Conversely, shaft 90 may be rotated in a clockwise direction, swinging the transfer pinion 102 on carrier plate 100 in mesh with pinion 110 thus rotating spindle 50 and its reel 46 to advance or rewind the film as the case may be.

The film gate actuating mechanism includes a cam disc 114, collar 116 and an intermediate leather washer 115, all loosely mounted upon a sleeve 118 which is secured at one end to beveled gear 94 and positioned axially of the shaft 92. A collar 120 is adjustably fixed to the free end of sleeve 118 to vary the tension of spiral compression spring 122 against the loosely mounted collar 116 to selectively adjust the friction drag on cam disc 114 as the sleeve 118 is rotated with the drive shaft 92.

The disc 114 is provided with a cam plate 117 for a purpose hereinafter explained and with a peripheral cam notch 124 in which rides a pin 126 adjustably carried by a rod 128 journaled in the wall 38 in the line of projection and to the upper end of which is secured a cam member 130 positioned between the glass plate supporting frames 74 and 75 of the film gate. The arrangement is such that, when even a slight turn is imparted to the drive shaft 90 to actuate the film advancing means through drive gear 94, cam disc 114 will frictionally tend to rotate therewith, moving pin 126 out of the notch 124 to the high portion of the cam periphery, the pin 126 in turn tending to rotate the cam 130 through the rod 128 to open the frames 74 and 75 carrying the glass plates 78 and 80. It should be noted that due to the swivel drive arrangement in conjunction with the film gate actuating mechanism, the plates always open before any advance is made in the film.

To return the cam disc 114 to normal position, a tension spring 132 is attached at one end to the cam disc and at its other end to an adjusting screw 134 threaded in a support 136 to approximately the level of the drive shaft 90. Thus, after initial movement of the disc 114 with the shaft 90 against the tension of spring 132 to actuate cam 130 and opening the film gate, the tension of spring 132 will overcome the frictional forces acting on the disc 114 to return the same to normal position when the shaft 90 remains stationary after the selected film advance and therewith return the cam 130 to normal position and closing the film gate.

To operate the projecting lens system for focusing the projected image, the inner end of shaft 92 extending axially beyond drive shaft 90 carries a worm 138 meshing with a pinion 140 fixed to one end of a rod 142 journaled in

the wall 38, the other end of which carries a pinion 144 meshing with rack 88 of the lens barrel 86. The shaft 92 is rotatable independently of the shaft 90 by a knob or the like 9 at its outer end, forming a common control center with the crank handle 11 so that either may be selectively manipulated by the operator with the same hand.

The mechanism for shifting the film vertically of its normal advance and rewind position, such as when scanning, comprises another novel arrangement including the provision of a pair of adjustable modified bell cranks 146 and 148, each pivotally mounted as by a piano hinge or the like 150 to opposite sides of the wall 38 and having bifurcated portions 156 and 158 extending underneath and supporting reels 46 and 48, respectively, so that the film is in full frame position in the film gate. The members 146 and 148 are eccentrically mounted on a disc 152 carrying a bevel gear 154 and supported within the head 30 by an arm 160. A complementary bevel gear 162 is keyed to the shaft 90 normally out of mesh with gear 154 but adapted to be urged into meshing engagement therewith when the operator forwardly presses upon the handle 11 to move shaft 90 axially inward a slight distance against the thrust of spiral compression spring 164 positioned at the opposite end of the shaft 92 adjacent the shaft support 166.

Rotary movement of the shaft 90 in a clockwise direction when thrust inwardly will tend to rotate the disc 152 through the gears 162 and 154 in a direction to retract the connecting arms of the bell cranks 146 and 148, elevating the bifurcated portions 156 and 158 thereof to raise the reels 46 and 48 thereby shifting the film upwardly or outwardly of its normal position in the film gate. Conversely, rotary movement of the inwardly thrust shaft 90 in a counter-clockwise direction will tend to rotate disc 152 in a direction causing the bifurcated portions 156 and 158 of the bell cranks 146 and 148 to lower the reels 46 and 48 thereby shifting the film downwardly or inwardly of its normal position in the film gate. Spring tensioned pivoted fingers 166 and 168 are carried by spindles 50 and 52, respectively, and so arranged with respect to the thrust of piano hinges 150 that when turned downwardly in abutment with the reels 46 and 48, the reels hold the film in normal full frame position in the film gate. The fingers 166 and 168 are adapted to be pivotally moved in alignment with spindles 50 and 52 to permit removal and replacement of the reels 46 and 48 when desired.

It will be apparent that when the shaft 90 is thrust inwardly, the sleeve 118 carrying the cam disc 114 will shift therewith to bring cam plate 117 into engagement with the end of pin 126 operating the film gate cam 130 so that when the shaft 90 is rotatably turned to either elevate or lower the film, the cam plate 117 will operate the cam 130 to open the film gate, the return movement thereof being the same as in the normal advance or rewind operation above described.

The operation of the device herein illustrated is believed readily apparent from the foregoing description and explanation thereof and it is understood that the embodiment of the invention herein disclosed is merely exemplary of the principles of the invention and capable of such modification as is within the scope of the following claims.

What I claim is:

1. A reading machine comprising, a cabinet, a screen mounted to slide inwardly and outwardly of said cabinet, a source of light emitting a beam of light, film advancing and rewinding mechanism including a film gate having plates each movable away from the film during film advancing or rewinding, an objective lens system for focusing an image carried by the film on said screen, a plurality of shafts telescoped one within another and relatively movable axially and rotatably to control said mechanism and said objective, and a head providing a support for said mechanism, objective and control shafts, said head being pivotally mounted relative to said cabinet to selectively position the film vertically or horizontally relative to said light beam.

2. In apparatus for projecting enlarged images on a screen including film advancing and rewinding mechanism and an objective lens system, the combination of a plurality of control shafts telescoped one within another and relatively movable axially and rotatably, each of said shafts having an operating handle or the like at the same end thereof, means for operatively connecting said film advancing and rewinding mechanism to one of said shafts, and means for operatively connecting said objective to another of said shafts.

3. In apparatus for projecting enlarged images on a screen including a condensed source of light, the combination of film advancing mechanism including a gate for intermittently holding the film across a beam of light from said light source, an objective lens for focusing an image carried by said film on a screen, a shaft rotatable to control said film advancing mechanism and operable to intermittently open said gate, and a second shaft telescoped within said first shaft and independently movable to focally adjust said objective lens.

4. In apparatus for projecting enlarged images on a screen including a condensed source of light, the combination of film advancing mechanism including a gate for intermittently holding the film across a beam of light from said light source, an objective lens for focusing an image carried by said film on a screen, a shaft rotatable to control said film advancing mechanism and operable to intermittently open said gate, and a second shaft telescoped within said first shaft and independently movable to focally adjust said objective lens, and means for mounting said mechanism, said lens and said shafts for rotary movement about said light beam while the film gate holding the film remains in the path of said light beam so that images carried either horizontally or vertically on said film can be produced on the screen in a horizontal position.

5. In a film reading machine, the combination of a film gate, a pair of spindles having film holding reels mounted thereon, means to selectively rotate said reels to advance or rewind the film through the gate, a pair of pivoted forked arms, the forks of each arm engaging and supporting one of said reels at opposite sides of its spindle, and means for pivotally moving said arms to raise or lower said reels whereby to selectively position the film in the film gate.

6. A reading machine cabinet comprising, a casing, a support for an image projector unit slideable inwardly and outwardly of the front end of said casing, a smooth-surfaced translucent screen

rigidly secured to the casing forming a wall portion thereof and disposed above said support, a front surfaced mirror in the rear end of said casing and opposed to said projector unit to reflect the projected image therefrom to said smooth-surfaced screen, said screen being adapted to support tracing paper for tracing of the image projected therethrough, a translucent viewing screen hinged exteriorly of the casing and swingable to rest on top of the casing or to overlay said first mentioned screen, a frame extending interiorly of the casing for supporting a sensitized medium for making prints of the projected image, said frame being slidably received in the front end of the casing between the said screens and said projector support, and a pair of coating mirrors hinged in the cabinet and shiftable to intercept the image from the projector and direct the same into the area of said frame.

7. In apparatus for projecting enlarged images on a screen including a condensed source of light, the combination of film advancing mechanism including a gate for intermittently holding the film across a beam of light from said light source, an objective lens for focusing an image carried by said film on a screen, a rotatable shaft operatively connected to said film advancing mechanism and to said gate whereby to open said gate and advance said film upon rotation of the shaft, a second shaft operatively connected to said objective lens whereby to focally adjust said objective lens upon movement of the second shaft, the shafts being telescoped one within the other and relatively movable axially and rotatably, and operating handles or the like for each of said shafts at adjacent ends thereof.

8. In apparatus for projecting enlarged images on a screen including a condensed source of light, the combination of film advancing mechanism including a gate for intermittently holding the film across a beam of light from said light source, an objective lens for focusing an image carried by said film on a screen, a shaft rotatable to control said film advancing mechanism and operable to intermittently open said gate, a second shaft movable independently of said first shaft to focally adjust said objective lens, the said shafts being telescoped one within the other, and means supporting said film advancing mechanism and said control shafts for movement about the axis of the light beam to project the images on said film in either horizontal or vertical position.

9. In apparatus for projecting enlarged images on a screen including a condensed source of light, the combination of film advancing mechanism including a gate for intermittently holding the film across a beam of light from said light source, an objective lens for focusing an image carried by said film on a screen, a rotatable shaft operatively connected to said film advancing mechanism and to said gate whereby to open said gate and advance said film upon rotation of the shaft, a second shaft operatively connected to said objective lens whereby to focally adjust said objective lens upon movement of the second shaft, the shafts being telescoped one within the other and relatively movable axially and rotatably, operating handles or the like for each of said shafts at adjacent ends thereof, and means supporting said film advancing mechanism, objective lens and said control shafts for movement about the axis of the light beam to project the images on said film in either horizontal or vertical position.

10. In a film reading machine, the combination

of a film gate, a pair of spindles having film holding reels mounted thereon, means to selectively rotate said reels to advance or rewind the film through the gate, a pair of arms each having a slotted portion at one end, the slotted ends each engaging and supporting the bottom of one of said reels with the reel spindle received in the slot, a rotatably mounted crank to which the opposite ends of said arms are pivotally secured, and means tending to rotate said crank to shift said arms into position to raise or lower said reels whereby to selectively position the film in the film gate.

11. In apparatus for projecting enlarged images on a screen including a condensed source of light, the combination of film holding reels, film advancing mechanism including a gate for intermittently holding the film across a beam of light from said light source, means for raising or lowering said film whereby to view selective portions of images thereon, an objective lens for focusing an image carried by said film on said screen, a plurality of control shafts telescoped one within another and relatively movable axially and rotatably, and a plurality of drive members carried by one of said control shafts, one of said drive members operatively connecting with said film advancing mechanism in one position of the control shaft and another of said drive members operatively connecting with said film raising or lowering means in another position of said control shaft, a second control shaft being operatively connected to said objective lens to focally adjust said lens.

12. In apparatus for projecting enlarged images on a screen including a condensed source of light, the combination of film holding reels, film advancing mechanism including a gate for intermittently holding the film across a beam of light from said light source, means for raising or lowering said film whereby to view selective portions of images thereon, an objective lens for focusing an image carried by said film on said screen, a plurality of control shafts telescoped one within another and relatively movable axially and rotatably, one of said control shafts being normally operatively connected to said film gate and film advancing mechanism whereby to open said gate and advance said film upon rotation of the shaft, the said shaft being movable into another position out of connection with said film advancing mechanism and into operative connection with said film raising or lowering means whereby to maintain said gate in open position and raise or lower said film upon rotary movement of the shaft and another of said plurality of control shafts being operatively connected to said objective lens to focally adjust said lens.

13. The apparatus of claim 11 wherein the film gate comprises a pair of transparent plates each simultaneously movable toward and away from the other.

14. A reading machine cabinet comprising, a casing, a support for an image projector unit movable inwardly and outwardly of the front end of said casing, a translucent screen forming a wall portion of the casing and disposed above said

support, a mirror in the rear end of said casing and opposed to said projector unit to reflect the projected image therefrom to said screen, said screen being adapted to support tracing paper for tracing of the image projected therethrough, a translucent viewing screen mounted on the exterior of the casing and movable to rest on top of the casing or to overlay said first mentioned screen, a frame extending interiorly of the casing for supporting a sensitized medium for making prints of the projected image, said frame being removably mounted in the casing, and a system of co-acting mirrors mounted in the cabinet, one of said mirrors being selectively shiftable into and out of optical alignment with the projector and the frame to intercept the image from the projector and direct the same into the second mirror and into the area of said frame.

15. A reading machine cabinet comprising a casing, a support for an image projector unit movable inwardly and outwardly of the front end of said casing, a translucent screen forming a wall portion of the casing and disposed above said support, a mirror in the rear end of said casing and opposed to said projector unit to reflect the projected image therefrom to said screen, said projector comprising a condensed source of light, film advancing mechanism including a gate for intermittently holding the film across a beam of light from said light source, an objective lens for focusing an image carried by said film, a shaft rotatable to control said film advancing mechanism and operable to intermittently open said gate, and a second shaft telescoped within said first shaft and independently movable to focally adjust said objective lens, and means for mounting said mechanism, said lens and said shafts for rotary movement about said light beam while the film gate holding the film remains in the path of said light beam so that images carried either horizontally or vertically on said film can be produced on the screen in a horizontal position.

16. A reading machine cabinet comprising a casing, a support for an image projector unit movable inwardly and outwardly of the front end of said casing, a translucent screen forming a wall portion of the casing and disposed above said support, a mirror in the rear end of said casing and opposed to said projector unit to reflect the projected image therefrom to said screen, said projector comprising a condensed source of light, film advancing mechanism including a gate for intermittently holding the film across a beam of light from said light source, an objective lens for focusing an image carried by said film, a rotatable shaft operatively connected to said film advancing mechanism and to said gate whereby to open said gate and advance said film upon rotation of the shaft, a second shaft operatively connected to said objective lens whereby to focally adjust said objective lens upon movement of the second shaft, the shafts being telescoped one within the other and relatively movable axially and rotatably, and operating handles or the like for each of said shafts at adjacent ends thereof.

ROBERT PLACE.
